This invention relates to a slushing scraper, and more particularly, to a slushing scraper of the type having arms detachably connected to the blade.

There are some slushing scrapers presently being used in which the arms are cast integral with or are permanently welded to the blade. However, such scrapers are not popular since they cannot be dismantled for convenient transportation underground. In another type of scraper in common use today, one or more bolts are used to attach each arm to the blade. The types utilizing a bolt connection are not entirely satisfactory since after the scraper has been in service for a period of time, the nuts frequently become frozen on the bolts, making the removal of bolts for dismantling purposes extremely difficult. Moreover, it has been found that some of the bolts tend to loosen or stretch in service, resulting in an expensive maintenance problem, and when very loose, in a sub-standard scraping operation.

It is an object of the present invention to provide an improved slushing scraper having a connecting means between the arms and the blade which permits the arms to be readily but soundly connected to the blade and to be easily disconnected from the blade even after a long period of service.

According to the present invention, there is provided a blade, a pair of arms, the blade and arms having integral interlocking sections which fit together as the front end portions of the arms are brought together during assembly of the scraper, and a clamping fixture for holding the front end portions of the arms together. The blade has a front transverse surface and a first interlocking section integrally formed at each end thereof, and the arms each have a rear end portion having a second interlocking section formed integrally therewith. Each of the first interlocking sections are engageable with one of the second interlocking sections to provide two pairs of interlocking sections for locking the blade and arms together. Each of the pair of interlocking sections defines interengageable fulcrum surfaces one each on the interlocking sections, and each pair of sections defines shoulder means including a plurality of mutually angular shoulders on one section of the pair, the other section of the pair of sections having shoulder engaging surfaces, each of the shoulder engaging surfaces being simultaneously engageable with one of the shoulders coincident with engagement of the fulcrum surfaces to constitute an interlock position in which engagement of the shoulders with the shoulder engaging surfaces prevents relative movement of the sections of the pair in any direction perpendicular to the front surface of the blade. The shoulder means includes a lug on one of the sections of the pair and a lug engaging wall on the other section of the pair for engagement with the lug in the interlock position. The lug and the wall are angularly disposed relative to the front surface of the blade for preventing movement of the second section in the interlock position in a direction parallel to the front surface of the blade. Each arm has a first position in which the shoulder means is freely movable into and out of engagement with the shoulder engaging surfaces and the lug is freely movable towards and away from the wall and a second position coinciding with the

2

interlocking position. The front end portions of the arms are in juxtaposed relation in the second position and the clamping means holds the front end portions together to thereby hold the fulcrum surfaces in engagement, the shoulder means in engagement with the shoulder engaging surfaces and the lug in engagement with the lug engaging wall.

In the drawings which show certain embodiments of the invention by way of example:

FIGURE 1 is a front perspective view of one embodiment of a slushing scraper according to the present invention;

FIGURE 2 is a fragmentary perspective view of the slushing blade of the embodiment of FIGURE 1, the arm being removed for the sake of clarity;

FIGURE 3 is a fragmentary perspective view of the arm of the embodiment of the slushing scraper of FIGURE 1, showing the rear end portion thereof;

FIGURE 18 is a fragmentary end view of the blade of the embodiment shown in FIGURE 17 but with the arm removed;

FIGURE 19 is a fragmentary side view of the arm in the embodiment shown in FIGURE 17 showing the rear end portion thereof; and

FIGURE 20 is a cross-sectional view through the connection of the arm and blade taken along the line XX—XX of FIGURE 17.

Referring now to FIGURE 1, reference character 30 denotes generally the slushing scraper which includes a blade member 31, a pair of arm members 32, 32 detachably secured to the blade member 31, and clamping means 33 for holding the forward ends of the arm members 32, 32 together. It is to be understood that the blade member as used herein is meant to include the item which is commonly called 'back plate or body in the industry.

The blade member in vertical cross-section is of opened U-shape having a central curved portion and contiguous leg portions 34, 34 so that the blade member has a convex back face 35 and a concave front face 36.

The side edges presented along the outer ends of the contiguous leg portions 34, 34 provide a pair of forwardly projecting scraping edges 37, 37. The scraping edges 37, 37 are preferably symmetrically disposed on opposite sides of a line bisecting the central curved portion of the blade. The scraping edges 37, 37 may both be plain edges, or they may both be toothed, or one may be toothed and one plain as shown in FIGURES 1 and 2, depending on the requirements of the mining operation.

The blade member 31, which terminates at opposite flat end edge surfaces 40, 40, has an interlocking section 38 formed integrally at each end. The front face of the blade member has at both ends a pair of beveled grooves 41, 41 (see FIGURE 2). The grooves 41, 41 are also disposed symmetrically on opposite sides of a line bisecting the central curved portion of the blade, and each groove 41 has an inner surface 42 slanting rearwardly from the front face of the blade to the end edge surface 40. Each end edge surface 40 has a hook-like member or lug 43 standing outwardly from the end edge surface 40 and projecting rearwardly. The lug 43 has a beveled forward edge surface 44 spaced forwardly from the back face 35 of the blade member 31 and slanting rearwardly away from the edge surface 40. The lug 43 has substantially parallel side edges 45, 45 spaced equally on opposite sides of a line bisecting the central curved portion of the blade member. A flat surface 46 is provided on the inside of lug 43 and the rearmost edge of the lug 43 is aligned with the back face 35 of the blade member. The back face 35 of the blade member is provided with a recess 47 which has a front flat surface 48 (see FIGURES 2 and 4) extending at right angles with respect to a line bisecting the central curved portion of the blade member. A side wall 49 of the recess opposed to the inner surface 46 of the lug 43 slants rearwardly and away from the lug 43 as can be best seen in FIGURE 4.

Although only one end of the blade member is shown in the drawings, it is believed no further comment is necessary in connection with the opposite end since the two ends of the blade member are identical except that they are a mirror image of each other.

The arm members 32, 32 are also identical except, as in the case of ends of the blade member, they are also a mirror image of each other. When assembled rear portions 50, 50 of the arm members 32, 32 are substantially parallel. The arm members 32, 32 have converging portions 51, 51 so that when assembled, the forward ends of the arm members are in close proximity to each other. The rear portions 50, 50, each of which have an interlocking section 49 formed integrally therewith, curve downwardly and the rearmost edge of the rear portions 50, 50 preferably conform in shape to the shape of the convex back face 35 of the blade member so that when the arm members are attached to the blade member, the rear edges of the arm members align with the back face 35 of the blade member.

Each arm member 32 has a flat side surface 52 (see particularly FIGURE 3) which engages the end edge surface 40 of the blade member when the arm member is attached to the blade member. A boss 53 is formed on the rearmost side surface 52 and has a rear edge conforming with the rear edge of the arm member. The boss 53 has a flat forward edge surface 54 for mating engagement with the front flat surface 48 on the recess 47 as shown in FIGURE 4. Each arm member 32 has an opening defined by opposed parallel side walls 55, 55 (see FIGURE 3), which are spaced slightly greater than the distance between the parallel side edges 45, 45 of the lug 43, and by a beveled front edge 56 slanting rearwardly away from the side surface 52. The opening in the arm member is shaped to receive in a snug manner the lug 43 when the side

surface 52 of the arm member is in engagement with the end edge surface 40 of the blade member and forward edge 54 is in engagement with the surface 48 in the recess 47. Preferably the lug 43 has the same thickness as the rear portion of the arm member so that the lug 43 completely fills the opening in the member and the outer surface of the lug 43 is flush with the outer surface of the arm member as shown in FIGURE 4. The boss 53 overlies a rear portion of the opening and thereby has a lug engaging surface 57 for engagement with inner surface 46 of the lug.

Spaced on opposite sides of the opening in the arm member and standing out from the flat side surface 52 are projections 60, 60. The projections 60, 60 are located and shaped to fit into grooves 41, 41 when the arm member is attached to the blade member and have rear beveled surfaces 61, 61 slanted forward and away from the side surface 52 for engagement with the surfaces 42, 42 of the grooves 41, 41.

The clamping means 33 can include a connecting mechanism which includes bolts well known in the field but is preferably of the type including a hollow box 62 and wedge 63 as shown in FIGURE 1 and described in co-pending United States application 259,960, filed Feb. 20, 1963, of John A. Wilson now Patent No. 3,164,914. By utilizing the clamping mechanism described in the above-mentioned application, no bolts whatsoever are used in the slushing scraper and the entire scraper can be knocked down very easily in the mine with the use of the only tool readily available to a miner underground, namely a sledge hammer.

To dismantle the completely assembled scraper, as shown in FIGURE 1, the wedge 63 is driven rearwardly with a sledge hammer and removed from between the forward ends of the arm members 32, 32. As described in the above-mentioned application, the hollow box 62 can then be removed from the forward ends of the arms permitting the forward ends of the arms to be separated. Once the hollow box 62 has been removed, the arm members can be pivoted about their rear ends since a tapered or radiused space is provided between the boss 53 on the arm member and the slanted side wall 49 of the recess 47 and since mating surfaces 42 and 61, and 44 and 56 are beveled. When the forward ends of the arm members 32, 32 are separated to the extent that the boss 53, on each arm member, engages the slanted walls 49 of its respective recess 47, the projections 60, 60 are free of the grooves 41, 41 and the forward edge of the lug 43 is out of the opening in the arm member. Each arm member can then be shoved rearwardly with respect to the blade member so that the arm member is separated entirely from the lug 43 and can be carried away from the blade.

To assemble the slushing scraper, each arm member 32 is brought up to the blade member from behind at its respective end of the blade member with the rear portion 50 extending outwardly at an angle with respect to end edge surface 40 of the blade member so that the boss 53 enters the recess 47 and the outer face of the boss 53 is in engagement with the slanted side wall 49 of the recess. As the boss 53 enters the recess 47, the rear part of the lug 43 enters the forward portion of the opening in the arm member in front of the boss 53. The forward ends of the arm members are then swung towards each other until they reach the position shown in FIGURE 1. As the arm members 32, 32 are pivoted about their rear ends, the lug 43 on the blade is entirely received in the opening of the arm member, so that the inner surface 46 of the lug engages the lug engaging surface 57 of the boss 53, the projections 60, 60 move into the grooves 41, 41 and the flat side surface 52 of each arm member comes into engagement with the end edge surface 40. The hollow box 62 is then pushed over the adjacent forward ends of the arm members and the wedge 63 inserted between the forward ends of the arm members and driven home to thereby lock all of the components together.

Once the forward ends of the arm members have been secured by the clamping means 33, the rear ends of the arm members are locked to the ends of the blade member in such a manner that substantially no play is permitted between the arm members and the blade members. The forward pull of the scraper is transmitted to the blade member from the arm member through the engagement of surface 54 of the boss 53 with the surface 48 in the recess 47 in the back of the blade.

The arm members cannot be separated from the blade member in a direction perpendicular to the end edge surfaces 40, 40 of the blade member since the lugs 43, 43 are hooked in behind bosses 53, 53 of the arm members. The inner surface 46 of the lug is in the same plane as the end edge surface 40, 40 and the arm members 32, 32 are so shaped that the flat side surface 52 of each arm member is held tightly against the end edge 40 of the blade member. Therefore, the lug engaging surface 57 of the boss 53 of each arm member is forced into tight engagement with the inner surface 46 of the lug. Thus, as the arms are brought to their final position, surfaces 40 and 52 act as interengagable fulcrum surfaces to cause surface 57 to move into tight engagement with surface 46 and thereby produce a snug interlock. To ensure snug engagement of the parts, the arms 32, 32 are preferably so shaped that they must be sprung together to permit the hollow box to be slipped over or removed from the ends of the arms. To facilitate the springing of the arms, the forward ends of the arms are provided with aligned openings 59, whereby a bolt can be inserted through the openings 59 when the forward ends of the arms have been drawn together by hand and a nut tightened on the bolt to spring the forward ends of the arms closer together.

The rear portions of the arm members cannot twist in a plane parallel to the end edge surfaces 40 of the blade member due to the fact the parallel side edges 45, 45 of the lugs are closely received between parallel side walls 55, 55 of the opening and also because projections 60, 60 are received in grooves 41, 41. The arm members are prevented from being pushed back off the blade member by engagement of beveled front edge 56 of the opening engaging the beveled forward edge surface 44 of lug 43 and also because of the engagement between the beveled surfaces 61, 61 of the projections 60, 60 and the inner slanted surfaces 42, 42 in the grooves 41, 41.

As indicated, the reception of the projections 60, 60 in grooves 41, 41 prevents twisting of the arm members with respect to the blade member and also prevents the arm members from being pushed back off the blade member, but since the reception of the lug 43 in the opening of the arm member also prevents these motions of the arm members with respect to the blade member as described above, the scraper will operate without the projections 60, 60 and the grooves 41, 41.

Since the interlocking elements at each end of the blade member are symmetrically disposed about the line bisecting the central curved portion of the blade member, the arm members can be disconnected from the blade member when one scraping edge becomes worn and the blade member can be turned end for end and inverted so that the arm members are connected to the end opposite to which they were previously connected and a new scraping edge is presented along the bottom. This operation can be conveniently performed underground with a sledge hammer and, of course, doubles the life of the blade.

The embodiment of the slushing scraper shown in FIGURES 5 to 8 is similar to the embodiment shown in FIGURES 1 to 4. Blade 31a is of the same shape in vertical cross-section as blade member 31 in that it is curved to present a concave front face 36a, a convex back face 35a, and a pair of forwardly projecting scraping edges 37a, 37a. The blade 31a, which also has opposed flat end edge surfaces 40a, 40a, includes an interlocking sec-

tion 38a at each end, one of which is shown in FIGURE 6. Blade 31a does not have a recess in the back face of the blade adjacent lug 43a. Instead the lug 43a, which has side surface 46a and edge surfaces 45a, 45a, extends rearwardly from the convex back face 35a so that its rearmost edge lies behind the convex back face 35a and is not aligned with it as in the case of lug 43a (see FIGURES 6 and 8).

Arms 32a, 32a, the rear portion 50a of one of which is shown in FIGURES 5, 7 and 8, are identical to arm members 32, 32 in that they converge forward of the blade and are adapted to be secured together by a clamping means at their forward ends. However, at the rear portion of the arms, the rearmost edge of interlocking section 49a does not conform to the convex back face 35a of the blade but extends rearwardly of the face 35a when the arm is fixed to the blade. The lug receiving opening in each arm 32a is forward from the rearmost edge of the arm but is identical in shape to the opening in the arm members 32 and has a beveled front edge surface 56a and side walls 55a, 55a. A boss 53a is formed on the side 52a of the arm 32a, but instead of having a flat forward edge surface as boss 53, boss 53a has concavely curved front edge surface 54a, as shown in FIGURE 7, which conforms to the convex back face 35a of the blade. The ends of the blades are provided with beveled grooves 41a, 41a disposed symmetrically on opposite sides of a line bisecting the central curved portion of the blade and each arm has a pair of projections 60a, 60a, for reception in the beveled grooves as described in connection with the previous embodiment.

In the embodiment of the slushing scraper shown in FIGURES 5 to 8, the arms are attached in the same manner described in connection with the previous embodiment, i.e., to attach the arms to the blade, each arm 32a is brought up to the blade with the rear portion thereof at an angle to the end edge surface 40a so that the rearmost portion of the lug 43a enters the opening in the arm forward of the boss 53a and the arm is pivoted until the lug 43a fully enters the opening in the arm and the projections 60a, 60a enter beveled grooves 41a, 41a. When lug 43a enters the opening, surface 46a engages surface 57a provided by boss 53a. The arms are also disassembled in the same manner in that their forward ends are separated and then the arms are pushed backward with respect to the blade so that the lugs 43a, 43a, are withdrawn completely from the openings in the arms.

A smooth back type of scraper such as that shown in FIGURES 1 to 4 is desirable in certain types of mining operations but the type shown in FIGURES 5 to 8 in which the arms stand out from the back of the blade is completely acceptable in many applications and has the advantage that the blade is of simpler construction, and this is quite important since the blade is the member of the scraper which is most frequently replaced.

FIGURES 9 to 13 show another type of slushing scraper of the type according to the present invention in which the arms stand from the back of the blade. The construction of blade 31b having a front transverse surface 36b and convex back face 35b in this embodiment has an interlocking section 38b and is merely identical to the construction of blade 31a of FIGURES 5 to 8, except that lugs 43b, 43b, one of which is shown in FIGURES 9, 10 and 13, are slanted rearwardly away from end edges 40b, 40b of the blade, i.e., lugs 43b, 43b at opposite ends of the blade are slanted towards each other. Lug 43b has edge surfaces 45b, 45b, and an outer side surface 43b' of each lug 43b commences at surface 40b and slants rearwardly away from side surface 52b of arm 32b when the arm is in the attached position. A second side surface 43b" of lug 43b is spaced inwardly of surface 43b' and is parallel thereto.

As is shown in FIGURE 9, the rear portion of arm 32b, which provides interlocking section 49c, does not conform in outline to the back face 35b of the blade but

extends rearwardly of the face 35b. A boss 53b is formed on the side surface 52b of the arm, and as in the case of the embodiment of FIGURES 5 to 8, the boss 53b has a concavely curved front edge surface 54b which conforms to the convex back face 35b of the blade. The arms 32b, 32b per se have no openings therein, but each boss 53b includes a bracket section 70 which forms an opening adjacent the side surface 52b and having side walls 55b, 55b for the reception of the lug 43b. Referring particularly to FIGURES 12 and 13 it can be seen that the bracket section presents a lug engaging surface 71 which opposes and slants rearwardly away from side surface 52b of the arm at the same angle as surface 43b". The forward edge of the bracket section 70 is beveled at 72 rearwardly and away from side surface 52b as shown in FIGURES 11 and 13.

Each arm 32b is assembled onto the blade in a manner similar to that discussed in connection with the two previous embodiments. The rear portion of the arm 50b is brought up to the blade from behind and at an angle with respect to surface 40b of the blade so that the side surface 52b is substantially in engagement with the side surface 43b' of the lug 43b. The rear portion of the arm is then slid forward at said angle with respect to the surface 40b of the blade so that the lug 43b is received in the opening between bracket section 70 and side surface 52b. Because of beveled portion 72, the arm can be slid forward at the angle in this manner until front edge surface 54b of the boss engages the convex back face of the blade. The arm is then pivoted to bring the forward ends of the arms together and thereby bringing side surface 43b" into engagement with lug engaging surface 71 of the bracket section 70, bringing side surface 52b into engagement with surface 40b of the blade and bringing projections 60b, 60b into beveled grooves 41b, 41b. To disconnect the arm from the blade the forward end of the arm is swung outward and the rear portion of the arm is then pushed backward at an angle substantially equal to the angle of the lug 43b.

The forward pull of the scraper is transmitted to the blade from the arms through the engagement of the front edge surfaces of the bosses 53b with the convex back face 35b of the blade. The arms cannot be separated from the blade in a direction perpendicular to the end edge surface 40b, 40b, because of engagement of surface 43b" of each lug, with lug engaging surface 71 of the bracket section, and the engagement between these same two slanted surfaces prevents the arm from being pushed back off the lug.

The slushing scraper of the embodiment of the invention shown in FIGURES 14 to 16 includes a blade 31c of very simple construction having at each end an interlocking section 38c. The blade 31c having a transverse front surface 36c and a concave back face 35c is of the same shape in vertical cross-section as the previously discussed blades, but in this embodiment the blade is formed with openings adjacent its opposite ends 40c and the lugs for reception in the openings are carried by rear portion 50c of the arms.

Each arm 32c has on its flat side surface 52c at the rear portion thereof a boss 53c. The forward edge surface 54c of the boss 53c is concavely curved to conform to the convex back face 35c. The boss 53c has a side surface 53c' spaced from the side surface 52c of the arm, and a forwardly projecting lug 43c is formed on the forward edge surface 54c. The lug 43c has edge surfaces 45c, 45c, and a side surface 43c' which commences at the side surface 53c', and slants forwardly and towards the side surface 52c of the arm. The lug 43c has a second side surface 43c" opposing the side surface 52c and substantially parallel to the side surface 43c'.

As indicated above, the blade has at each end an opening for the reception of the lug 43c. The opening is slot shaped and is defined by end wall surfaces 55c, 55c spaced just slightly greater than the width of the lug 43c

and opposed slanted side surfaces 78 and 79 (see FIGURE 16). The side surface 78 is slanted forwardly and towards the adjacent end of the blade at an angle equal to the slant of side surface 43c" with respect to side 52c.

5 Side surface 79 slants forwardly and towards the adjacent end of the blade at a greater angle than side surface 78 so that the rear portion of the arm can be turned at an angle with respect to the end edge surface of the blade when the arm is being attached or disassembled. The end edge surface of the blade is beveled towards the back face of the blade at 80 adjacent the boss 53c to permit the turning of the arm with respect to the blade when lug 43c is received in the opening of the blade during the assembling or disassembling operation.

10 15 The movements of each of the arms 32c, 32c during the assembling or disassembling operation are the same as described in connection with the embodiment of the invention shown in FIGURES 9 to 13 and will not be described again at this time. When the forward ends of the arms are secured together the arms cannot be separated

20 from the blade in a direction perpendicular to the side surface 52c because of the engagement of surfaces 43c" and 78 and the engagement of these same two slanted surfaces prevents the arms from being pushed back off the blade. The other forces which occur between the arms and the blade are taken up as described previously in connection with the other embodiments of the invention.

25 Referring now to the embodiment of the invention shown in FIGURES 17 to 20, it will be noted that this embodiment provides for a smooth back type of scraper having an interlocking section 38d at opposite ends of the blade, but that it differs from the embodiment shown in FIGURES 1 to 4 in that the lug receiving openings are in the blade and the lugs are carried by the arms.

30 35 As in the previously discussed embodiments the blade 31d has in vertical cross section a curved central portion and contiguous leg portions (see particularly FIGURE 18). At opposite ends of front transverse surface 36d a web member 86 extends between the leg portions 34d,

40 45 40d and is flush at one side with end edge surface 40d of the blade. Rear edge 87 of web member 86 is spaced from the curved central portion of the blade and slants rearwardly and away from the end edge surface 40d (see FIGURES 18 and 20). At each end of the blade there is provided a lug receiving opening which is defined by opposed end wall surfaces 88 and 89 and opposed side surfaces 90 and 91 (see FIGURES 18 and 20). The surface 91 which is spaced inwardly from the edge surface 40d slants rearwardly and away from surface 40d while side surface 90 is substantially parallel to surface 40d.

50 55 50 As in the case of the first described embodiment, the rearmost edges of the arms 32d, 32d, the rear portion 50d of one of which is shown in FIGURES 17 and 19, conform in shape to the convex back face 35d of the blade so that these edges are aligned with the back face when the arms are attached to the blade. At the rear end of each arm, a step portion is formed providing the lugs (FIGURES 19 and 20). Each arm 32d has a flat side surface 52d and an outstanding part or boss 53d formed

60 65 60 thereon. The boss 53d has an outline of the same shape as the opening formed between web member 86 and the curved central portion of the blade, and a forward edge surface 54d of the boss is beveled rearwardly and away from side surface 52d for mating engagement with rear edge 87 of web member 86. The boss 53d is of the same thickness as web members 86, and has a flat outer surface which is, therefore, flush with the inner surface of the web when the arm is fastened to the blade. Lug 43d is, which has edge surfaces 45d, 45d, formed on the flat outer surface of boss 53d, and as can be seen from FIGURES 19 and 20 the forward edge surface of the lug is beveled at the same angle as the forward edge surface 54d of boss 53d and is a continuation of the beveled forward edge surface 54d. The lug 43d has an outer

70 75 70 side surface which is parallel to the side surface 52d and

spaced therefrom a distance just slightly less than the distance between side surface 90 of the opening and end surface 40d of the blade. Rearmost surface 43d" of the lug 43d (see FIGURE 20) is slanted rearwardly and away from side surface 52d at an angle approximately equal to the slant of side surface 91 of the opening and is arranged to be immediately adjacent the side surface 91 when side surface 52d of the arm engages end surface 40d of the blade. The angle of bevel of the front edge surface 54d and the front edge surface of the lug 43d is greater with respect to side surface 52c as can be seen in FIGURE 20.

When the arms are being connected to the end of the blade, the lug 43d of interlocking section 49d of each arm is inserted into the space between web member 86 and the curved central portion of the plate and during this operation the forward ends of the arms are kept separated as in the previous cases so that the side surfaces 52d, 52d of each arm are at an angle with respect to the end edge surfaces 40d, 40d of the blade. After the lugs 43d of each arm is inserted into the space behind web member 86, each arm is turned about its rear portion so that the forward ends of the arms come together and side surface 52d moves toward end edge surface 40d. At the same time the rear portions of the arms are pushed rearwardly a small amount which moves boss 53d into the space behind web member 96 and lug 43d into the opening in the blade. Eventually side surface 52d comes into complete engagement with end edge surface 40d, boss 53d is completely received in the space between the web member 86 and the curved central portion of the blade and the lug is received in the opening in the blade as shown in FIGURE 20 as the forward ends come to their clamping position. The required movements to separate the arms from the blade are, of course, the exact reverse of those just described.

As indicated above, the embodiment of FIGURES 17 to 20 is a smooth back type scraper as is the embodiment of FIGURES 1 to 4. In some respects the blade construction of the embodiment of FIGURES 17 to 20 is simpler, but it has the disadvantage of the connecting means being stressed to a greater extent than all of the previously described embodiments. Unlike all of the previously described embodiments, the pulling force is not transmitted to the blade by engagement of the boss with the back surface of the blade. In this last embodiment, the pulling force is transmitted to the blade through the engagement of beveled surface 54d of the boss 53d with beveled surface 87. Because surfaces 54d and 87 are at an angle with respect to the direction of pull, a component of force is developed which tends to separate the arm from the blade in a direction perpendicular to the side surface 52d. This force is taken up by engagement of surface 43d" with side surface 91 of the opening, which, of course, produces additional stresses in the lug 43d.

The reception of the shoulders of the boss in the shoulders surrounding the opening formed by web 86 and the curved central portion prevents the arm from twisting in a plane parallel to side surface 52d, and the engagement of surfaces 43d" and 91 prevent the arm from being pushed back off the blade.

It can be readily appreciated from the above description that present invention provides for a slushing scraper which can be easily assembled and disassembled. Since it can be easily disassembled and reassembled underground, transportation of the scraper is facilitated or any part can be readily replaced or taken to the surface for repair. Moreover, with the constructions described, the blade can be easily inverted underground so that a new scraping edge is presented when the first edge becomes worn.

We claim:

1. A slushing scraper comprising
  - (a) a blade having
    - (i) a front transverse surface, and

- (ii) a first interlocking section integrally formed at each end thereof,
  - (b) a pair of arms each having
    - (i) a forward end portion, and
    - (ii) a rear end portion,
  - (c) each said rear end portion having a second interlocking section formed integrally therewith,
  - (d) each of said first sections being engageable with one of said second sections to provide two pairs of interlocking sections for locking said blade and arms together in an interlocking position,
  - (e) means for clamping said blade between said rear end portions of said arms comprising
    - (i) a fulcrum surface defined by each of said interlocking sections and angularly disposed relative to said front surface,
    - (ii) said fulcrum surfaces of each said pair of sections being engageable with each other to define a clamping position of said arms and blade,
    - (iii) a lug on one of said sections of each pair thereof having a surface angularly disposed relative to said front surface,
    - (iv) a wall surface engageable with said lug surface on the other section of each pair thereof, and
    - (v) a clamping fixture for holding said front end portions together thereby to hold said fulcrum surfaces in engagement and said lug and wall surfaces in engagement,
  - (f) means for preventing movement of said blade in a first direction forwardly and rearwardly of said arms when the arms and blade are in the clamping position comprising
    - (i) a first pair of opposed shoulders on one of said sections of each pair thereof each having a surface lying in a plane intersected by any plane perpendicular to said front surface, and
    - (ii) a surface engageable with each said shoulder surface on the other of said sections of each pair thereof,
  - (g) and means for preventing movement of said blade with respect to said arms in a direction perpendicular to said first direction comprising
    - (i) a second pair of opposed shoulders on one of said sections of each pair thereof each having a surface lying in a plane intersected by said first shoulder surface planes, and
    - (ii) a surface engageable with each said second shoulder surface on the other of said sections of each pair thereof,
  - (h) each said arm having free swinging movement in a direction towards and away from said blade on disengagement of said clamping fixture from said arms,
  - (i) said blade and arms in said clamping position having said fulcrum surfaces in engagement, said lug and wall surfaces in engagement, and said shoulder surfaces and said shoulder engaging surfaces in engagement.
2. A slushing scraper as defined in claim 1, wherein the rear end portion of each arm has a side surface and said blade has an end surface at each end thereof, said side surface of each arm and one of said end surfaces providing said fulcrum surfaces of each of said pair of interlocking sections, wherein said lug is formed integrally on and projects rearwardly from said blade, and wherein in each said arm has a bracket formed on said side surface thereof and having a front surface providing one of the surfaces engageable with one of said first pair of shoulders, said front surface of said bracket being engageable behind said blade, said bracket providing said wall surface and defining a lug receiving opening between said rear portion of said each arm and said wall, said wall and said lug in said clamping position slanting rearwardly and away from said side surface of said arm.

3. A slushing scraper as defined in claim 2, wherein the shoulders of said means for preventing movement of the blade in a direction perpendicular to said first direction at least in part comprise projections on said side surface of each arm, each projection having a beveled rear surface slanting forwardly and away from said side surface, aid wherein said second shoulder engaging surfaces are at least in part provided in the front surface of said blade by beveled grooves at both ends thereof slanting rearwardly to said end surfaces for reception of said projections.

4. A slushing scraper as defined in claim 2, wherein said blade has a central curved portion in vertical cross-section so that said front face is concave and the rear face is convex.

5. A slushing scraper as defined in claim 4, wherein the forward edges of the brackets are concave to conform to the rear face of the blade.

6. A slushing scraper as defined in claim 4, wherein the blade has two side edges forming forwardly projecting scraping edges, and said interlocking sections are disposed symmetrically about a line bisecting said curved portion.

7. The slushing scraper as defined in claim 1, wherein the rear end portion of each arm has a side surface and said blade has an end surface at each end thereof, said side surface of each arm and one of said end surfaces providing said fulcrum surfaces of each pair of interlocking sections, and wherein each arm has a boss formed on the side surface and having a front face providing one of the surfaces engageable with one of said first pair of shoulders, said front face being engageable behind said blade, wherein said lug is formed integrally on the front face of said boss, and wherein said blade has a lug receiving opening extending thereto from behind, said opening being defined in part by said wall surface, said wall and lug in said second position slanting forwardly toward said side surface of said arm.

8. A slushing scraper as defined in claim 7 wherein said blade has a central curved portion in vertical cross-section so that said front face is concave and the rear face is convex.

9. A slushing scraper as defined in claim 8 wherein the front faces of the bosses are concave to conform to the rear face of the blade.

10. A slushing scraper as defined in claim 8, wherein the blade has two side edges forming forwardly projecting scraping edges, and said interlocking sections are disposed symmetrically about a line bisecting said curved portion.

11. A slushing scraper as defined in claim 1, wherein said lug is included in a stepped portion on one of said sections of each pair of interlocking sections, and wherein the other of said sections is provided with a stepped portion receiving opening being defined at least in part by shoulders of said first and second pairs, said stepped portion having faces providing said shoulder engaging surfaces.

12. A slushing scraper as defined in claim 11, wherein the rear end portion of each arm has a side surface and said blade has an end surface at each end thereof, said side surface of each arm and one of said end surfaces providing said fulcrum surfaces of each pair of interlocking sections, wherein said stepped portion includes an outstanding part on said side surface of the arm with the lug being laterally spaced from said side surface and projecting rearwardly from said outstanding part, and wherein said opening is formed in said end surface of said blade.

13. A slushing scraper as defined in claim 12, wherein the blade has a curved central portion and two contiguous leg portions in cross section, wherein a web member at each end of said blade extends between the leg portions and provides in part said end surface of said blade, each web being spaced from said curved central portion to form said opening in said end surface, wherein said outstanding part has an outline for mating reception

5 in said opening formed by said web and said curved central portion, and wherein said curved central portion of said blade has a rearwardly extending, lug receiving opening in said front surface and inward from the end of said blade, said lug receiving opening being defined in part by said lug engaging wall surface.

10 14. A slushing scraper as defined in claim 1, wherein the rear end portion of each arm has a side surface and said blade has an end surface at each end thereof, wherein said each arm has an outstanding part on said side surface, said outstanding part having a front face providing one of the surfaces engageable with one of said first pair of shoulders, said front face being engageable behind said blade in said clamping position, and wherein the shoulders of said means for preventing movement 15 of the blade in a direction perpendicular to said first direction at least in part further comprise projections on said side surface of said each arm, said second shoulder engaging surfaces being in part provided by projection 20 receiving grooves in said end surface of said blade.

15 15. A slushing scraper as defined in claim 1, wherein each rear end portion of said arms has inner and outer side surfaces and is provided with a lug receiving opening defined in part by surfaces providing said second pair 25 of shoulders and extending between and being substantially perpendicular to said side surfaces, wherein said lug is integrally formed on said blade member and has opposite parallel side faces providing said second shoulder engaging surfaces, and wherein a boss is formed on said 30 side surface of the arm, said boss partially overlying said opening to define said lug engaging wall surface.

16 16. A slushing scraper, comprising a scraper blade member having front and rear faces, end surfaces and a scraping side edge, a pair of arm members having side 35 surfaces at rear portions thereof, and locking means for separably securing said arm members to said blade member with said side surfaces of each of said arm members in engagement with one of said end surfaces, said locking means including a boss formed on the side surface of each arm member and having a forward edge for engagement with said rear face of said blade, and a pair of lugs formed at opposite ends of the blade and projecting rearwardly from said rear face, each lug having a boss engaging side surface and a beveled forward edge spaced 40 forwardly from said rear face and slanting rearwardly from the end surface of the blade, said arm members each having an opening therein for reception of one of the lugs when said side surfaces are in engagement with said end surfaces, each boss having a portion overlying a 45 rear portion of the opening for engagement with the boss engaging surface of the lug when the lug is received in the opening to prevent separation of said arm members from said blade member in a direction perpendicular to said side surfaces, said openings having a beveled front edge slanting rearwardly away from the side surfaces for 50 engagement with said beveled forward edge of the lug.

17 17. A slushing scraper comprising a scraper blade member having front and rear faces, end surfaces and a scraping side edge, a pair of arm members each having a forwardly projecting portion and a rear portion having a side surface, and locking means for separably securing said arm members to said blade members together with the side surfaces in engagement with the end surfaces, said locking means including a boss formed on the side 55 surface of each arm member and having a forward edge surface for engagement with said rear face of said blade, a lug formed at each end of the blade and projecting rearwardly from said rear face, said lugs having a boss engaging side surface, each of said arm members having an opening therein for reception of one of said lugs when its side surface is in engagement with one of the end surfaces, each boss having a portion overlying a rear portion of said opening for engagement with the boss engaging surface of said lug when said lug is received in said opening to thereby prevent separation of 60

said arm members from said blade member in a direction perpendicular to said side surfaces, the front surface of said blade having beveled grooves at both end surfaces, said grooves having an inner surface slanting rearwardly to the respective end surface, and a projection on the side surface of each arm member for reception in one of the grooves and having a rear beveled surface slanting forward and away from said side surface for engagement with the slanting surface of the grooves when said side surfaces are in engagement with said end surfaces.

18. A slushing scraper comprising a scraper blade having front and rear faces, end surfaces and a forward projecting scraping edge along a side edge, two arm members having normally juxtaposed forward ends and rear side surfaces, and locking means for separably securing said arm members to said blade with the side surface of each arm in engagement with one of the end surfaces of said blade, said locking means including a boss on said surface of each arm having a forward edge for engagement with the rear face of said blade, a rearwardly projecting lug formed at each end of the blade, each lug having a boss engaging side surface in the plane of the adjacent end surface of the blade, and a beveled forward edge spaced forwardly from said rear face and slanting rearwardly from the adjacent end surface, the arm members each having an opening therein for reception of said lug when said side surfaces are in engagement with said end surfaces, the boss on the side surface of each arm member having a portion thereof overlying a rear portion of said opening for engagement with the boss engaging portion of the lug when said lug is received in said opening to thereby prevent separation of said arm members in a direction perpendicular to said side surfaces, said opening having a beveled front edge slanting rearwardly away from the side surface for engagement with the beveled forward edge of said lug, and a projection on the side surface of each arm having a rear beveled surface slanting forward and away from said side surface, the front face of the blade having beveled grooves in both end surfaces

for reception of the projections, said grooves having inner surfaces slanting rearwardly to the end surfaces for engagement with the beveled surfaces of the projections when said side surfaces are in engagement with said end surfaces.

5 19. A slushing scraper as defined in claim 18 wherein said blade has a central curved portion in vertical cross-section so that said front face is concave and said rear face is convex.

10 20. A slushing scraper as defined in claim 19, wherein said arm members have rear edges extending rearwardly of said rear face when said arm members are separably secured to said blade and the forward edge of said boss is concavely curved to conform to the rear convex face of the blade.

15 21. A slushing scraper as defined in claim 19, wherein the arm member and the boss have aligned rear edges conforming in outline to the curved central portion of the blade, and the rear face of the blade is provided with a recess adjacent said lug for the reception of said boss with the rear edges of the boss and arm member aligned with the back face of the blade.

20 22. A slushing scraper as defined in claim 19, wherein said blade has two side edges forming forwardly projecting scraping edges, and said locking means is disposed symmetrically about a line bisecting said curved portion.
